UNITED STATES PATENT OFFICE.

GUY J. EVANS, OF BUFFALO, NEW YORK.

ADDRESSING MACHINE.

Application filed April 30, 1919. Serial No. 293,711.

To all whom it may concern:

Be it known that I, GUY J. EVANS, a citizen of the United States, residing in Buffalo, in the county of Erie and State of New York, have invented new and useful Improvements in Addressing Machines, of which the following is a specification.

This invention relates to an addressing machine which is more particularly designed for addressing a plurality of cards, tags or the like with the same address for use in shipping a plurality of detached articles to the same place, although the machine may be also used for other purposes.

It is the object of this invention to produce a machine for accomplishing this purpose in an expeditious and efficient manner and by means which are compact and simple in construction and capable of being manufactured at low cost.

In the accompanying drawings: Figure 1 is a top plan view of an addressing machine constructed in accordance with my invention. Figure 2 is a transverse section of the same taken on line 2—2, Fig. 1. Figure 3 is a top plan view of the stencil which is employed in this machine for successively placing the same address on a plurality of cards or tags.

Similar characters of reference refer to like parts throughout the several views.

4 represents a horizontal table which forms the main support of the machine and which is preferably made of wood; although any other suitable material may be employed if desired. On its underside this table is provided with a plurality of legs 5 whereby the same may be mounted on any available surface. The cards, tags, or similar articles

6 upon which the address is to be printed are preferably mounted in the form of a stack or pile on the table adjacent to its rear left hand corner. For the purpose of keeping this stack in order so that the cards or

tags may be conveniently removed successively from the top thereof, the left hand edge of the table is provided with an up-right wall 7 against which the left hand side of the stack abuts and from the rear edge 50 of the table a rear wall 8 projects upwardly

and forwardly in an inclined position so that upon piling a stack of cards or tags with the rear side of the same against this rear wall the stack as a whole will lean forwardly and thereby cause the several cards or tags to be off-set relatively to each other in a forward direction, which enables the operator to conveniently and rapidly pick off the top card or tag successively from the pile for presentation to the mechanism whereby the address is printed thereon.

These cards or tags are placed upon the rear right hand part of the upper side of the table which serves as the printing place or platen of the apparatus. In order to present these cards uniformly to this printing mechanism a gage device is provided which preferably consists of a longitudinal gage bar 9 arranged lengthwise over the front part of the table and adjustably secured thereto so as to be capable of moving this gage bar either forwardly or backwardly relatively to the printing position, this adjustment being preferably effected by means of two guide or adjusting arms 10, 10 projecting forwardly from the gage bar adjacent to opposite ends of the same and two screws 11, 11 working in threaded sockets in the table and passing through transverse slots 12 in the guide arms.

The printing of the address on the cards or tags while the latter are arranged on the printing place on the platen is effected by means which comprise a stencil having a comparatively stiff sheet-like frame or body 13, such as strong and tough paper, and a stencilizable sheet or diaphragm 16 which is secured to the body of the stencil across a printing opening 15 formed in the front part of this stencil body or frame. The address

to be printed may be formed in this stencilizable sheet in any suitable manner, for instance, by cutting the same therein or forming the same thereon by an ordinary typewriter which operates to remove particles of the tissue of the stencilizable sheet so that when this sheet is placed over the card or other article which is to be addressed and an ink bearing device is passed over the upper side of the stencil sheet, this ink will

- pass through the address openings of the stencil and leave the stencil impression on the object underneath. The ink may be applied to the stencil and to the article to be 5 addressed in any suitable manner but preferably by means of an ink roller 19 which is mounted on a suitable movable frame 20 having a handle 21 for manipulating the same.
- 10 The stencil is preferably held in its proper position over the printing position of the table by providing the stencil adjacent to its rear edge with a pair of openings 14 which receive two pins 18, 18 rising from the rear 15 part of the table. By this means a pivotal connection is produced between the stencil and the table which permits the front end of the stencil to be raised for placing the card to be printed underneath the same and then 20 lowered upon said article preparatory to producing a stencil impression thereon. The body or frame of the stencil is preferably made comparatively long so that a considerable area 17 is formed thereon between the 25 printing opening 15 of the stencil and the pivot openings 14 on which surface suitable entries may be made, such as shipping instructions, which pertain to the particular address of this stencil.
- 30 For the purpose of conveniently applying the stencil to and removing the same from the upper side of the successive cards or tags which are to be addressed, means are provided for raising and lowering the stencil. For this purpose a vertically movable carrier 22 is employed having preferably the form of a flat plate which is constructed of sheet metal, this plate being placed over the upper side of the stencil and provided adjacent to its rear edge with a pair of pivot 40 openings 23 which receive the pivot pins of the table. A longitudinal channel 24 is arranged on the underside of this plate at the front edge thereof, which channel opens 45 rearwardly and receives the front edge of the stencil body. An opening 25 is arranged in the front part of this carrier between the channel and pivot openings 23 and in a position to register with the printing address 50 of the stencil. Upon raising or lowering this carrier the address stencil rises and falls with the same at which time the pins 18 and the openings in the stencil and carrier through which they pass serve as a pivotal 55 connection between the table and the carrier and stencil.
- 60 Projecting rearwardly from the rear part of the stencil carrier is a lifting arm 26 preferably constructed in the form of a rod and arranged at an angle to the plane of the carrier as a whole. On this arm is mounted a weight 27 which is adjustably secured thereto by means of a screw 28 passing through the weight and engaging with the lifting rod. This weight may be adjusted 65 inwardly or outwardly on the rod 26 to properly lift the carrier and stencil when the latter are free to move. The pivot openings in the stencil and carrier are preferably sufficiently large to permit of the requisite 70 rocking movement of the carrier and stencil relatively to the table so that the weight 27 can lift the stencil to such a position as will permit the attendant to conveniently place the cards or tags upon the printing position 75 on the table and remove the same therefrom.
- While the carrier and stencil are in an elevated position, as represented by dotted lines in Fig. 2, the attendant places a card, tag or other article upon the printing place 80 of the table in engagement with the gage bar after which the attendant presses the inking roller 19 downwardly against the upper side of the carrier so as to bring the stencil in engagement with said article and then passes 85 the inking roller under pressure across the printing opening in the carrier and in engagement with the exposed printing area of the stencil, whereby the ink from this roller will penetrate the printing openings in the 90 stencil and leave an imprint on the article to be addressed corresponding to the inscription on the stencil. The attendant now raises the ink roller from the carrier which permits the weight 27 to lift the carrier and 95 stencil from the card, tag or other article which has been addressed leaving the latter free to be removed by the attendant and replaced by another article from the supply stack. In this manner it is possible to 100 quickly apply the same address upon a plurality of cards or tags which are to be attached to a number of articles designed for shipment to the same party.
- When it is desired to write another address on the cards the stencil in the apparatus may be readily removed therefrom by lifting the carrier and the stencil then in use, off from the pivot pins and then replacing the stencil by another one bearing the 105 desired address.
- As a whole this machine is exceedingly simple in construction, it is not liable to get out of order and it permits of expeditiously addressing tags or the like at a minimum 110 of cost.
- I claim as my invention:
1. An addressing machine comprising a table having a printing position and pivot pins rising therefrom in rear of said position, a plate shaped carrier movable bodily vertically toward and from said printing position and provided at its rear edge with a pair of pivot openings which receive said pins, and also capable of swinging laterally 115 on said pins, and means for mounting a stencil on said carrier.
  2. An addressing machine comprising a

table having a printing position and pivot pins rising therefrom in rear of said position, a carrier movable vertically toward and from said printing position and provided at its rear edge with a pair of pivot openings which receive said pins, a rearwardly opening channel on the underside of its front edge and a printing opening between its

front and rear edges, and an address stencil arranged on the underside of said carrier 10 with its printing area in register with said printing opening and having its front edge engaging with said channel and its rear edge provided with pivot openings which receive said pivot pins.

GUY J. EVANS.
